**LIBRARY INDEX CARD FILE KNOB AND
ROD RETAINER**

Robert C. Bencene and Malcolm T. Phelps, Jamestown, N.Y., assignors to Weber-Knapp Company, Jamestown, N.Y.

Filed July 22, 1964, Ser. No. 384,473
2 Claims. (Cl. 129—16)

This invention relates to drawer type filing devices; for example, letter or legal files, or files of the type which are sometimes referred to as library index card files; and more particularly to an improved form of separator or card holding rod and locking arrangement therefor. For example, the present invention relates to improvements in devices such as are shown in U.S.A. Patent 818,090 of April 17, 1906 and British Patent 10,051 of May 8, 1908.

As disclosed for example in the prior patents referred to, a file typically employs a horizontal wire or rod for holding the filed cards or separators in place; the front end of the rod extending through an aperture formed in the file drawer header and being provided externally of the drawer with a control knob portion or the like. Internally of the drawer the rod is preferably given a second point of sliding support so as to maintain it in horizontal attitude and at a raised elevation above the floor of the drawer. This effect is typically obtained by simply arranging to slide-fit the rod into an aperture through the rear wall of the drawer, or through the conventionally employed card follower which comprises some form of positionally adjustable and upright standing partition device. The present invention relates to improved means for snap-locking the rod in place as it reaches its fully inserted position in the drawer, which lock means must be released by manual displacement in a direction transverse to the axial direction of the rod.

Therefore, it is a primary object of the present invention to provide in a file drawer of the character described, improved means for releasably locking the file rod in operative position.

Another, more specific object, is to provide an improved holding means as aforesaid comprising a simple ferrule type holder device adapted to be easily mounted within the drawer header aperture, and cooperating means on the rod knob and in the holder for positively preventing unintended displacements of the rod.

Another object is to provide an improved device as aforesaid wherein the ferrule-like holder incorporates a novel combination lock and spring member which is operable to bias the rod in improved manner into locked position.

Another object is to provide an improved device as aforesaid wherein the combination lock and spring member simply snap-fit into secure assembly with the holder member against rotational and/or axial movement relative to the holder.

Another object is to provide an improved device as aforesaid which is inexpensive to manufacture; involves the use of no rivets, screws, weldments or the like; and yet is rugged and durable and fail-proof in operation.

Other objects and advantages will appear in the specification hereinafter which describes one form of the invention as illustrated by the accompanying drawing wherein:

FIG. 1 is a vertical sectional view taken longitudinally through a card filing drawer, and illustrating a card holding rod equipped with the locking device of the present invention;

FIG. 2 is a fragmentary enlarged scale view of the rod knob and lock portion of the device of FIG. 1, showing by solid lines the rod knob in its normal or locked position, and by broken lines the rod knob in its released position;

2

FIG. 3 is a fragmentary sectional view taken as along line 3—3 of FIG. 2; and

FIGS. 4 and 5 are perspective, disassembled, views of the two components of the rod holder and lock unit of the invention.

As shown in the drawing herewith, the rod and retainer device of the present invention may be employed in connection with an index card filing drawer shown by way of example in FIG. 1 to comprise a bottom plate 10; side plates 12; rear plate 14; and a header plate 16. It will be appreciated that the drawer may be of any desired construction, but will in any case include a header plate apertured at a position adjacent to but somewhat above the bottom level of the drawer so as to accommodate in slide-fitting relation therethrough a card holding rod as indicated at 18. Also, as indicated at 19 (FIG. 1), the drawer will preferably be equipped with a positionally adjustable "card follower," which will also be apertured at the same elevation. Hence, the rod 18 will be slidably supported in horizontal attitude slightly above the bottom level of the drawer, and is thus adapted to slide-fit through registering apertures in the index cards or the like which are to be filed in the drawer. Thus, the cards are held against accidental displacement from the drawer, while removal and/or additions to the card file may be easily made by temporarily withdrawing the rod 18 from its operative position as shown in FIG. 1.

The present invention has to do with the knob or front end of the rod and to the detachable locking means located in the drawer header. As shown best in FIG. 2, the rod knob includes a pull portion 20 for manual gripping and control of the rod as will be explained more fully hereinafter. The knob pull portion 20 is located at the extreme outer end of the rod 18 and thus meets in abutting relation with the drawer header 16 when the rod is in operative position. The knob portion of the device also includes a reduced diameter neck portion 22 located intermediate of the pull 20 and an enlarged shoulder portion 24. The shoulder portion 24 is formed in sharp right angled relation to the reduced neck portion 22 and is subtended rearwardly by a tapered shank portion 26.

To detachably lock the rod in operative position as shown in FIGS. 1, 2, 3, a two-piece lock unit is provided. The first component comprises a generally cylindrical-shaped holder as indicated at 30 which is provided to have an outstanding periphery flange portion 32 at its outer end. The outside diameter of the body of the member 30 is such as to snugly slip-fit into the cylindrical bore or aperture formed through the drawer header 16; and thus when the holder 30 is pressed into the drawer aperture, the end flange 32 abuts the outer face of the header and thereby positions the holder as shown. To lock the holder member 30 against accidental displacement from mounted position within the header 16, it may be upset or shape-deformed in any preferred manner, whereby the deformed metal of the member 30 will lock into the material of the drawer header and prevent accidental displacement of the holder from the drawer.

The second component of the rod lock unit comprises a novel spring member as illustrated best in FIG. 5. This member is formed of spring steel or the like and comprises a generally cylindrical-shaped piece having opposite curved side walls 36, 36 joined integrally by a flat bottom wall 38. A pair of spring fingers as indicated at 40, 40 are formed to extend axially of the device from the inner edge of each side wall portion 36, 36; and the parts are so dimensioned and arranged that when the spring member is force-fitted into the holder member 30 to its operative position as shown in FIG. 2, the spring fingers 40, 40 extend radially inwardly toward the longi-

tudinal center line of the unit. Hence, whenever the rod 18 is inserted through the lock unit and towards the operative position as shown in FIGS. 1-3, the tapered shank portion 26 of the rod knob initially springs the arms 40, 40 upwardly and outwardly until such time as 5 the enlarged shoulder portion 24 slips over the rear edge of the flat bottom plate 38, and then downwardly therebehind as shown in FIGS. 2, 3. This action locks the knob and rod unit against accidental release of the rod knob relative to the spring component of the lock unit.

In order to release the rod from the lock unit, the pull portion 20 is simply raised upwardly as to the broken line position thereof shown in FIG. 2, during which action the spring fingers 40, 40 are again forced upwardly and outwardly until the lower edge of the shoulder 24 15 clears the inner edge of the flat bottom plate 38. Hence, by first lifting up on the pull 20, and then pulling forwardly thereon, the card holding rod 18 is easily displaced and withdrawn relative to the drawer.

To hold the spring component of the lock unit in 20 place relative to the holder sleeve 30, the top wall portion of the sleeve 30 is coined inwardly to provide depressed ceiling portions as indicated at 42, 42 interconnected by a depressed ridge portion 44. Also, the opposite sides of the wall of cylinder 30 are inwardly deformed as indicated at 34 (FIGS. 2, 3, 4) to provide dwells into which the sides of the spring member snap-fit, when in assembled relation. Also, when the spring member is force-fitted into the sleeve 30 as to the position shown in FIG. 2, the upper ends of the curved side walls 30 35 36, 36 of the spring member snap-fit into the ceiling areas which are bounded by the depressed areas 42, 42, 44; thereby firmly locking the spring member in the holder 30. To facilitate entry of the rod and knob unit through the spring member incidental to card replacements or the like, the front edge of the spring member is preferably formed with an inclined ramp as indicated at 46.

Thus, it will be appreciated that by virtue of the present invention a structurally simple rod holding device is provided such as may be inexpensively manufactured and 40 assembled while featuring the advantage of being positive and sure and fail-proof in operation. No rivets or screws or weldments or the like are required in the construction; and the rod locks in operative position by simply snap-fitting thereto, and is released therefrom by the simplest of manual procedures involving first lifting the knob 20 and then pulling forwardly. It is a particular feature of the invention that the spring fingers 40, 40 biasing the rod down into locked position operate automatically to center the rod relative to the lock unit and to the aperture through the drawer header. Thus, the 45 spring action insures properly centered locations of the rod head 20 at all times, and thereby contributes to the ornamental appearance of the complete file.

We claim:

1. In an index card file of the type having a container including a front wall provided with an aperture and a holder rod extending through said aperture into the interior of the container,

a rod retainer disposed within said aperture, said rod retainer comprising a cylindrical holder fixed to said front wall within said aperture and a separate spring member disposed within said holder, said holder including an inwardly projecting and axially extending ridge between its opposite ends and a pair of spaced, opposed abutment members projecting inwardly adjacent the opposite ends of said ridge, said spring member comprising an elongate strip of spring material of generally U-shaped form having a flat intermediate portion bridging the interior of said holder in chordwise relation thereto, said spring member also having arcuate opposite end portions engaged in contiguous relation with inner surface portions of said holder and terminating in spaced opposite end edges straddling said ridge to orient said spring member with respect to said holder and preclude relative rotation therebetween, said spring member being disposed in captive relation between said abutment members to axially orient said spring member within said holder,

said spring member also including a pair of spring fingers extending from that side edge of the spring member facing the interior of the container and adjacent respective ones of said end edges of the spring member, said spring fingers being inclined inwardly toward the axis of said holder,

said holder rod terminating in a knob limiting inward axial disposition of the rod, said rod including a cylindrical neck of a diameter to be received, with radial clearance, within the confines of said spring member and a bulbous head joined to said neck and presenting a radially disposed annular abutment face at the juncture of said neck and bulbous head,

said spring fingers being engaged with said bulbous head to normally maintain said neck against said flat intermediate portion of the spring member when said rod is in its limited position of axial inward displacement, and said annular abutment surface being spaced from said knob to position the abutment surface inwardly of but closely adjacent to the inner edge of said flat intermediate portion of the spring member when the rod is in such position.

2. A rod retainer as defined in claim 1 including an inclined ramp member on the rear edge of said flat intermediate portion of the spring member.
